[57] CLAIM

The ornamental design for a clearance checking tool for air brake system, as shown.

DESCRIPTION

FIG. 1 is a front perspective of a clearance checking tool for air brake system, showing my new design;
FIG. 2 is a top plan view thereof;
FIG. 3 is a side elevational view thereof;
FIG. 4 is an opposite side elevational view thereof;
FIG. 5 is a bottom plan view thereof;
FIG. 6 is a front elevational view thereof; and,
FIG. 7 is a rear elevational view thereof.

FIG. 1.

FIG. 2.

FIG. 3.

FIG. 4.

FIG. 5.

FIG. 6.

FIG. 7.
